Design No. 319. Charles G. Frazee, design for Plates for Registers, Ventilators &c. —
James S. Bailey, 3, Patented, Sept. 24, 1850. —

Figure No 5

Dec. 319

Tuttle & Bailey of Williamsburgh N.Y. U.
Letters Patent. No. 319. Dated Sept. 24. 1850.

The Schedule referred to in these Letters Patent and making part of the same.

To all whom it may concern:

Be it known that we Charles F. Tuttle
& James S. Bailey (Tuttle & Bailey) both of Williamsburgh Kings County, State of New York,
have invented or produced the configuration or design hereinafter described which design is a configuration
of open scroll or fret work, used as the front or surface plates of Hot Air Registers and Ventilators and
for other useful and ornamental purposes.

The said design is substantially described by the drawing
annexed to these specifications which is marked Figure 5.

In the drawing, we have given a birds eye view
of the whole Register but it is only the design of the open or scroll work for which we ap-
ply for Letters Patent.

We wish to patent this design without reference to its size.
We wish to secure this design without reference to
the position of the wheel or the receipt or border usually formed around it, as said wheel
or receipt may be removed or situated at the middle or other part of the surface of
the Register.

We would state that this design we have had in use
in connection with Charles F. Tuttle's Patent Register but for a period for less than two years that it
has been our intention to apply for Letters Patent when we had our designs complete and perfected and have
stated this fact to others and do not consider that we have abandoned said design to the public.

What we claim and desire to secure by Letters Patent is the
particular configuration or design of open scroll or fret work substantially as described by the annexed draw-
ing and alluded to in the foregoing specifications, the said design is used by us as the top or front plate of
Hot Air Registers and Ventilators and for other useful and ornamental purposes.
